WEB FEEDING, TENSIONING, AND FORM
ALIGNING APPARATUS

Walter A. Konerman, Cincinnati, and Ellis S. Rump and Arthur L. Farr, Hamilton, Ohio, assignors to The Miami Systems Corporation, Hamilton, Ohio, a corporation of Ohio

Application December 6, 1930, Serial No. 500,566

3 Claims. (Cl. 197—133)

This invention relates to a web feeding, tensioning and form aligning apparatus for the continuous form printed webs of billing machines of the type embodied in the well known Underwood and 5 other flat platen and other billing machines.

An object of our invention is to produce such a device as will feed several superposed webs in a manner that will insure accurate alignment of the forms printed thereon, with the least possible 10 effort by the operator, with a minimum of time expenditure, and with less damage to the webs than is occasioned by other devices of the general type known to us.

A further and more specific object of our invention is to produce a machine of the type disclosed, 15 in which the operator is relieved of much of the manual detail work involved in operating the machine, thereby permitting of the operator giving exclusive attention to the actual form aligning, and recording operations attendant in operating the machine.

These and other objects are attained in the device described in the following specification and illustrated in the accompanying drawings in 20 which:

Fig. 1 is an elevational view, partially in section, showing a machine of the type to which we have referred, equipped with our invention.

Fig. 2 is a perspective view, upon an enlarged 30 scale, of the portion of the machine incorporating the features of our invention which involve the automatic or semi-automatic functioning thereof.

Fig. 3 is a perspective view of the same portion shown in Fig. 2, certain covers having been re- 35 moved to disclose interior mechanism, the view being taken from the back of this portion.

Fig. 4 is a perspective view of the same portion shown in Fig. 3, and from the same face, but at a different angle.

Figs. 5, 6, 7 and 8 are detail elevational views 40 showing parts of our improved apparatus in the different positions they assume during operation of the device.

This is an invention relating to that type of 45 machine which is specifically illustrated and described in copending application serially numbered 332,180, which was filed January 12, 1929, was executed by Ellis S. Rump and Arthur L. Farr, and is entitled Web aligning and tensioning 50 device. In the specification and claims herein set forth, there is described an improvement upon the device to which we have just referred, which, although not involving any changes in the structure thereof, does materially improve the operation 55 and consequently the functioning of the de-

vice in that several advantages are attained. These improvements are attained by applying to the aforesaid mechanism a power equipped unit wherein manual operation, variation of performance, and other objectionable features are largely, if not entirely, overcome.

The frame of the billing machine embodies two rearwardly extending side rails 11 and 12 which mount the web tensioning and aligning control device 13 which has been described in the application identified above. The control device herein illustrated consists of substantially identical elements to those shown in the copending application, but is somewhat different therefrom in that the feed rollers 14 are located above the tensioning or snubbing rollers 15 of the control device instead of in horizontal alignment. This is conducive to an easier threading of the webs between the rollers of the device, as well as contributing greatly to the ease of movement of the control 75 device and passage of webs therethrough.

At the rear of the side rails 11 and 12 is mounted the power unit 16 by means of which the control device is caused to function. This unit is framed by a casing having the shape shown in 80 Figs. 2, 3 and 4, which extends from one side rail to the other and is attached thereto. A motor 17 which drives the device, is mounted on the casing, and, through gears 18 and 19 drives a shaft 20 having bearing in the housing 21 forming a portion of the casing. A loose pulley 22 which acts as a drum upon which a belt 23 is wound for moving the control device to the rear of the mounting frame of the billing machine, is rotatively mounted on the shaft 20, but is controlled by a clutch 24 which connects it with shaft 20 upon operation of grooved clutch collar 25 by yoke 26. This yoke 26 is operated by slight rotary movement of shaft 27 which has projecting arm 28 for accomplishing this movement. 95 Arm 28 engages a notch 29, as shown in Fig. 3, or a fork 30, as shown in Fig. 4, which is carried by a rod 31 reciprocally mounted on the frame of the machine and connected by a cable or link 32 to the foot treadle 33 of the machine. 100

Associated with the motor is a switching mechanism for controlling it. This is shown especially in Fig. 4 and consists of an insulating block 34 which mounts two switch levers 35 and 36 pivotally on pivots 37 and 38 respectively located 105 between their ends. Movement of lever 35 is controlled by movement of arm 28 through its connection therewith by means of a block 39 on arm 28, and a pin 40 on the block and extending into a socket 41 in the lower end of lever 35. 110

Movement of lever 36 is controlled by a spring 42 bearing against it to move it in one direction, and a pin 43 which, when pushed, will move it in the opposite direction. Pin 43 is reciprocally mounted in the frame of power unit 16 and extends through it to the front thereof, beyond which it extends to be engaged by a finger 44 carried by control device 13. A yielding contact 45 on lever 35, affords the proper yielding and essentially perfect electrical contact to assure proper control of the motor 17 at such times as it is necessary to have it function. Disclosure of an electric circuit including the motor and switch elements has not been made for the reason that it is not a part of the invention disclosed and is but a simple matter quite obvious to one skilled in the art.

In operation, the parts shown are in normal position and condition, which means that treadle 33 is in elevated position as shown in Fig. 1, with arm 28 in backward position, permitting clutch 24 to assume engaged condition under influence of spring pressure from the clutch spring. Normal position and condition also means that switch lever 35, because of the backward position of arm 28, occupies a position such as shown in Fig. 5, while switch lever 36, because of the engagement of pin 43 therewith, under pressure by finger 44 of control device 13 when it is in normal rearward position, occupies a normal position away from lever 35 and consequently in broken circuit relation therewith. The roll of stationery having had its several webs arranged as shown in Fig. 1, with one as propelling web preferably, and the others occupying merely draped condition, is thus also normally ready for use of the apparatus.

Of course, the first operation of the operator is to fill in the web forms on the platen 45, by using the typewriter 46, as is usual. After the forms on platen 45, by using the typewriter 46, have been filled in, the typewriter is pushed back to allow knife 47 to raised and the superposed webs on the platen to be disengaged from the hooked aligning pins 48 with which the apparatus is equipped. The raising of knife 47 is accomplished by means of treadle 33 which accomplishes the results described, when depressed by the operator's foot. With the raising of knife 47, cable 32 draws upon rod 31 and causes fork 30 to move arm 28 forwardly, thereby moving switch lever 35 to the greatest tilted position shown in Fig. 6, simultaneously therewith, causing clutch yoke 26 to draw upon clutch collar 25 to compress the clutch spring and disengage the clutch 24. This operation therefore frees loose pulley 22, and, because of the snubbing action of web 50 on rollers 52 and 53, allows web control device 13 to move forwardly as the webs are pulled forwardly by the operator in order to bring a set of fresh forms into position. Forward movement of the control device moves finger 44 from pin 43 and allows switch finger 36 to move to the position shown in Fig. 7, preparatory to a closing of the switch by lever 35 as will be explained shortly. It may be pointed out that belt 23 which is wrapped on loose pulley 22, is attached to control device 13 in some such manner as shown in Figs. 1 and 2, and that the control device is provided with a forwardly extending finger 49 which engages the frame of the typewriter to arrest forward movement of the control device and to permit rearward movement of the typewriter to move the control device rearwardly, also as will be explained presently.

The filled in forms having been drawn from the platen, and new forms having been placed thereon with their registering apertures located over the aligning pins 48, the control device 13 is now caused to be moved backwardly by releasing treadle 33, which allows cable 32, rod 31, and arm 28 to be moved rearwardly by the clutch spring functioning to engage clutch 24, and, through block 39, pin 40, socket 41, and lever 35, to close the switch as shown in Fig. 8. The resultant operation is then to start motor 17 and, through gears 18 and 19, and clutch 24, to cause pulley 22 to wind up belt 23 as the control device is drawn rearwardly. Rearward movement of the control device is permitted without restraint by the horizontal portions of the webs, because the snubbing action effected by the webs to cause the control device to be moved forwardly when the webs have been drawn manually over the platen, has been overcome due to clamping of the webs by knife 47 in connection with pins 48, the power of motor 17 being sufficient to cause the webs to slip between rollers 52 and 53 as device 13 moves rearwardly. This slippage is the amount which occurs equal to the total backward movement of the control device and actually is the amount of feed given the webs during each cycle of operation of the apparatus described above. As the control device is caused, automatically, thus to move rearwardly, the one web 50, which is the taut web and acts to rotate the stationery roll 51, is drawn upon by its assigned rollers or bars 52 and 53 of the control device, thereby unwinding sufficient of the webs to re-establish the necessary amount of drape of the remaining webs, preparatory to a repetition of the placing of fresh forms in position on the platen as has been explained. Just before the control device reaches its rearward limit, its finger 44 engages pin 43 and pushes it rearwardly, thereby again moving lever 36 to the position shown in Fig. 5, and thus breaking the circuit and stopping motor 17. The entire sequence of operations is now repeated as has been described.

It may be well to call attention to the fact that the details of construction of the control unit constitute no part of the invention herein described, inasmuch as these features have already been described in a copending application to which we have referred above. It also may be advisable to draw attention to the fact that such a power driven mechanism as that which we have just described, is as readily applicable to other forms of the same general control mechanism which are well known and in common use in connection with billing machines of the long established type.

Having thus described our invention what we claim is:

1. In combination with a platen adapted to receive and position a plurality of superposed webs from a source of supply, a web tensioning and aligning apparatus comprising a control device for feeding the webs and adapted to travel toward the platen under manual operation and away from the platen under power operation, a source of power, a power driven means connected with the control device, and a second means functioned upon completion of the manual operation to connect the source of power with the power driven means, all said parts being so arranged and related that feeding of the webs will be accomplished by movement of the control device by the power driven means.

2. In combination with a platen adapted to

receive and position a plurality of superposed webs from a source of supply, a web tensioning and aligning apparatus comprising a control device for feeding the webs and adapted to travel 5 toward and away from the platen under manual and power operation respectively, a source of power, a power driven means connected with the control device, a second means functioned upon completion of the manual operation to connect 10 the source of power with the power driven means, all said parts being so arranged and related that feeding of the webs from the source of supply will be accomplished by movement of the control device by the power driven means, and a plurality 15 of elements between which the webs are threaded, carried by the control device, snubbing the webs upon movement of the control device toward the platen and allowing slippage of the webs between the elements upon movement of the control device 20 away from the platen.

3. In combination with a platen adapted to receive and position a plurality of superposed webs from a source of supply, a pair of guide rails extending rearwardly from the platen, a web tensioning and aligning apparatus comprising a control device adapted to travel on the guide rails, a plurality of bars on the control device, between which the webs are threaded, said control device being movable toward the platen under manual operation and away from the platen under power operation, a source of power, 25 a power driven means connected with the control device, and a second means functioned upon completion of the manual operation to connect the source of power with the power driven means, all said parts being so arranged and related that feeding of the webs from the source of supply will be accomplished by permitting web passage 30 between the bars upon movement of the control device by the power driven means.
